UNITED STATES PATENT OFFICE.

DAVID B. BIRD, OF CHICAGO, ILLINOIS.

POWDER-GUN.

1,301,366.

Specification of Letters Patent. Patented Apr. 22, 1919.

Application filed May 11, 1918. Serial No. 233,904.

To all whom it may concern:

Be it known that I, DAVID B. BIRD, a citizen of the United States, residing at Chicago, in the county of Cook and State 5 of Illinois, have invented certain new and useful Improvements in Powder-Guns, of which the following is a specification.

The invention has for an object to effect improvements in devices for ejecting disinfecting materials or other materials from containers, and has for an especial object to give an appliance adaptable to use in dispensing or ejecting materials of various degrees of viscosity and fluidity. It is a particular purpose of the invention to give a device which will be highly efficient in the projection of pulverized material. Another important aim of the invention is to give a desirable construction in such devices whereby the ejector device may be detachably connected with a container element so that after the emptying of the container a new one may be put in place upon the ejector device, or enabling the ready refilling 25 of the container, if preferred. A specific object of the invention is to give an improvement in the means for compressing and projecting air into a container, whereby great strength will not be required to attain 30 a maximum air pressure in the device, nor great speed in its operation, and liability of clogging minimized.

A further aim is to give an efficient construction and arrangement of the elements 35 so that a maximum agitation of pulverized material will be assured, with resultant efficiency and economy in action of the appliance.

In addition to seeking to cheapen and simplify such devices, while retaining a maximum of efficiency, other objects, advantages and features of invention reside in the construction, arrangement and combination of parts as hereinafter described, and shown 45 in the drawings, wherein,

Figure 1 is a longitudinal sectional view of one embodiment of my invention,

Fig. 2 is a similar view of an additional form thereof,

Fig. 3 illustrates a further modification.

There is illustrated in Fig. 1 a disinfectant spraying device comprising a hollow spherical element 10, ordinarily formed of rubber, and having at opposite sides coaxial 55 integral nipples 11 and 12. Upon the first of these a metal sleeve 13 is engaged, hav-

ing a closure cap or plug 14 therein provided with a broadened operating head 15 having knurled edges, and provided with a hang up ring 16 in a convenient situation 60 to engage over a nail or hook, to suspend the device when not in use. Inserted into the plug 14, there is a tube 17, extending diametrically across the bulb 10, and through the opposite nipple 12, to a short distance 65 outwardly thereof, at which end the tube is exteriorly threaded and has engaged thereon a nozzle 18, provided with an inwardly projecting flange 19 engaging snugly around the nipple 12 for rotation 70 thereon when the nozzle 18 is being screwed into position. Within the bulb 10 the tube is provided with rings 20 revoluble upon the tube, between which one or more connecting rods 21 are extended, and upon these 75 rings there is mounted a helical spring 22 attached to the respective rings by its opposite ends, the spring being of a length and being bent to lie in an arc closely adjacent or against the inner wall of the bulb 10, which 80 spring may be used as an agitator and pulverizer. The tube 17 is formed with large ports 23 intermediately of its length, through which air and dust may pass outwardly through the nozzle 18 when the 85 bulb 10 is compressed. Immediately outward of these ports toward the nipple 11, the tube is closed by means of a suitable plug 24, and outwardly of the plug in the same direction a port 25 is formed in the tube 90 adapted to permit the passage of material therethrough when introduced through the adjacent end of the tube after removal of the plug 14.

In the use of this form of the device, it 95 may be filled by removing the plug 14 and pouring the powder into the open end of the tube 17, the powder passing through the port 25 and into the bulb 10. It is preferably filled to a point on a level with the 100 side of the ports 23 next the nozzle, when the device is held in a position with the nozzle pointed vertically downward. The proper amount of powder being introduced and the cap replaced, by giving the bulb a 105 rotary motion, the inertia of the spring 22 will cause it to rotate upon the tube 17, agitating the powder in the bulb and creating a dense dust therewithin. During or after such rotary movement of the bulb, it may be 110 squeezed, thus causing a rush of air carrying the dust with it, through the ports 23 and

out through the nozzle 18. This operation may be repeated as often as desired.

In Fig. 2 there is shown a modified form of the device in which the nozzle 18' is provided with a tubular inner termination 17' closed at its inner end, and stopping short of the inner side of the bulb a distance opposite the mouth of the nozzle. The bulb is formed the same as before described, 10 the nipple 11' having the sleeve 13' thereon within which there is engaged a plug 14' similar to that before described. Around the base of the nozzle at its point of engagement through the nipple 12', a compressor 15 ring 26 is fitted, serving to hold the nipple tightly upon the nozzle and preventing relative movement of the latter within the nipple. The tubular portion 17' of the nozzle element is ported as dotted at 28, and 20 able upon this part of the nozzle there is a sleeve 29, stopping short of the inner wall of the bulb adjacent the nozzle mouth a suitable distance for the functions described later, and having attached thereto the ends 25 of band springs 30, bent into circular form and as nearly concentric with the bulb 10 as possible, and spaced a short distance inwardly thereof, as shown, small springs 31 being utilized to hold the sleeve at its inner 30 position.

In the use of this last described form of the device, a suitable amount of powder having been introduced, the bulb may be given a reciprocatory motion upon the axis of the 35 nozzle, and on account of the loose mounting of the sleeve 29 upon the tubular portion 17', the springs 30 will thereby be given a relative reciprocating movement within the bulb serving to efficiently agitate the material 40 therein. The port 28 is normally spaced such a distance within the tube 29 that it will not be uncovered except when the sleeve 29 is at the outer limit of its movement toward the mouth of the nozzle. By grasping 45 the bulb 10' lightly in the hand, and rotating it alternately in opposite directions upon the axis of the nozzle, without abrupt and rapid movement, the agitator 30 will, by its inertia be caused to rotate relatively 50 within the bulb, striking the particles of matter therein, and assisting further in the process of agitation. After agitation of the powder in this device, pressure upon the sides of the bulb 10 will force the sleeve 29 55 outwardly after compressing the air within the device. This pressure is to be exerted so as to bear upon the opposite side of one of the springs 30, which will cause them to assume an elongated oval form, either moving 60 the sleeve 29 outwardly upon the tubular portion 17' sufficiently to uncover the port 28, or insuring the maintenance of the sleeve 29 in open position.

In Fig. 3 there is illustrated a further form 65 of device, in which the hollow spherical ele-

ment 10^a may be formed of metal or rubber or corresponding material as found desirable and compression of air within the device is attained by means of a diaphragm 31 mounted in the outer enlarged or flared end 70 of a rigid bell 32, the diameter of which is sufficient to give the desired capacity to the device, and also to serve as a base, upon which the device may be set up when desired. The diaphragm 31 may be formed 75 of any material suitable for the purpose, rubber having been used therein, and attached to the center thereof there is a reciprocating rod 33 having a ported valve 34 upon its inner end reciprocable in a tube 35 80 mounted diametrically in the bulb 10^a. The tube 35 is secured into the bell 32, and the latter is secured upon the bulb 10^a in a suitable manner. The tube 35 is projected through the bulb opposite the bell, and has 85 mounted thereon a nozzle 18^a, similar to the nozzle 18 before described. The tube 35 is provided with a plurality of ports 36 therein, located adjacent the middle of the bulb 10^a, the valve being of a length to cover these 90 ports when in neutral position, and provided with ports 34' on its sides normally spaced toward the diaphragm from the ports 36. The valve is formed with a passage leading from the ports 34' through the outer end 95 of the valve. A port 37 is formed in the tube 35 a distance back of the valve toward the diaphragm when in initial position, and means is provided at 38 on the bell in the form of a ported cap having a cap and ball 100 valve screwed into a tube 39, for admitting air to the bell when a partial vacuum is created therein. An agitator 22' including a mounting 20' may be mounted upon the tube 35, corresponding to the spring 22 and mounting 20 before mentioned. This agitator may be caused to rotate within the bulb by giving the appliance a rapid orbital movement on an axis parallel to that of the nozzle, or by rotating it rapidly in first one 110 direction and then the other, on the axis of the nozzle. Disinfectant may be introduced into the bulb 10^a by unscrewing the cap of the valve 38, and removing the valve parts, leaving a clear passage way into the bell 115 32. The spray device may be turned to a vertical position, allowing the disinfectant to pass into the tube 35, and through the port 37 into the interior of the bulb 10^a.

In this form of the device, pressure upon the rod 33 will bear the diaphragm 31 inwardly, compressing air within the bell and causing it to pass inwardly through the port 37 with a forcible movement serving to agitate the material within the bulb, and after 125 the air has been considerably compressed, the valve port 34' will register with the port 36 permitting an abrupt outrush of air from the bulb through the valve and tube and nozzle, as will be readily understood. In 130

this manner, the objection to a great many appliances of this kind that sufficient pressure cannot be developed to project disinfectant material a desired distance, is obviated, while at the same time giving the device a nozzle of large capacity without requiring excessively large air compressing means. In prior devices where a large nozzle has been used, the air often escapes therethrough before it has been possible to compress it to the desired extent, on account of the inability of the operator to work the compressing means with sufficient rapidity to insure the action desired. With my device, a slow compression of the air will nevertheless result in a powerful and rapid flow of the air and disinfectant through the nozzle, so that venting through the ports 36 will occur when one-third or one-half of the maximum pressure is developed, or other ratio, as found desirable.

The spring 22 and its counterparts in the various forms of the device will rub caked or lump material against the side of the spherical element, quickly reducing the material to a fine powder, ordinarily.

The arrangement of the device so that the material ejected will lie below the outlet opening to the nozzle prevents the contents from piling over the orifice.

It will be noted that by the connection between the nipples of the ball containers, when the ball is compressed, the neck por-

tions will be expanded within the flanges of the nozzle and closure cap, forming an effective seal.

What is claimed is:

1. In a powder gun or the like, a hollow resilient collapsible container, a tube thereacross ported centrally within the hollow member and projected therefrom, and a collapsible resilient agitator revolvable on the tube, whereby the container and agitator may be grasped and plied.

2. In a device of the character described, a container circular in cross section, a concentric ported outlet tube therein and a helical spring arranged on a curve concentric with the container, and close to the inner surface thereof, and revolvably mounted on the tube.

3. In a device of the character described, a container circular in cross section, a concentric ported outlet tube therein and a resilient agitator arranged on a curve concentric with the container, and close to the inner surface thereof adapted to rub against the side of the container, and revolvably mounted on the tube.

In testimony whereof I have affixed my signature in presence of two witnesses.

DAVID B. BIRD.
